UNITED STATES PATENT OFFICE.

WILLIAM L. HITCHCOCK, OF PORTSMOUTH, OHIO.

BAFFLE OR ARCH FOR LOCOMOTIVE FIRE-BOXES.

1,202,386.

Specification of Letters Patent.

Patented Oct. 24, 1916.

Application filed August 12, 1915. Serial No. 45,210.

To all whom it may concern:

Be it known that I, WILLIAM L. HITCHCOCK, a citizen of the United States, and a resident of Portsmouth, in the county of Scioto and State of Ohio, have invented certain new and useful Improvements in Baffles or Arches for Locomotive Fire-Boxes; and I do hereby declare the following to be a full, clear, and exact description 10 of the invention, such as will enable others skilled in the art to which it appertains to make and use the same.

My invention relates to an improvement in baffles or arches for locomotive fire boxes, the object being to provide a refractory arch which can be readily and quickly installed in a fire box; which when installed will be locked against accidental displacement of any of its parts, and which is constructed 20 to deflect the products of combustion against the arch tubes and thoroughly and rapidly mix such products before they pass to the top of the arch.

With these objects in view my invention 25 consists in the details of construction as will be more fully described and pointed out in the claims.

In the accompanying drawings, Figure 1 is a view in plan showing the baffle or arch 30 supported on the arch tubes; Fig. 2 is an end view of the same; Fig. 3 is a view in section on the line A—A of Fig. 1; Fig. 4 is a perspective view of one of the intermediate bricks; Figs. 5 and 6 are views in section of 35 same; Fig. 7 is a view in perspective of one of the side or end bricks and Figs. 8 and 9 are views in section of the latter.

In the present instance I have shown four arch tubes 1 communicating at their ends 40 with the boiler, and arranged in two pairs, one pair being at each side of the longitudinal center of the fire box, the space between the inner tubes of the two pairs being greater than the space between the tubes of 45 each pair, and also greater than the space between the outer tubes of each pair and the side sheets 2. This arrangement of tubes is however not essential.

The arch rests upon the arch tubes, and 50 is composed of a central longitudinal row of bricks 3, of the same dimensions, two intermediate rows 4 of the same dimensions and two outer rows 5, all of them being of 55 such size as to be conveniently handled and passed through the fuel door of the fire box.

The bricks of the central and intermediate

rows 3 and 4 are alike, except that the bricks of the center row may be longer than those of the intermediate rows, and each is provided on its lower face with a plurality of 60 ribs 6 forming a series of grooves or channels which extend lengthwise the bricks and transversely of the fire box, and operate to retard and thoroughly commingle the products of combustion in their passage under 65 the arch, and also to direct the said burning and highly heated products transversely and into direct contact with the arch tubes 1 and assist in heating the same. The opposite ends of each of the bricks 3 and 4, are beveled upwardly and inwardly, and each is provided at each end with a mortise 7 preferably rounded as shown; at one side edge with a tenon 8 also preferably rounded, and at its opposite side with a mortise 9 shaped 75 to receive the rounded tenon 8 on the next adjacent brick in its row. The mortises 7 and 9, and tenon 8 of each brick are in the same horizontal plane so as to render them interchangeable, and the ribs 6 on the underside of the central and intermediate rows of bricks are cut away at their extreme ends as at 10, to form curved seats which rest on the arch tubes 1 as clearly shown in Fig. 2, the seats being of less depth than the ribs so 80 as to leave passage ways between said ribs over the arch tubes 1.

The bricks 5 of the two outer rows also have ribs 6 which align with the ribs on the bricks 3 and 4 in the assembled arch, and 85 these ribs are continued up at the outer ends of the bricks as at 11, and are slightly inclined, so that when the outer bricks are assembled in their inclined positions as shown in Fig. 2, the ribs 11 will be approximately 90 parallel with the side sheets 2, and form side channels through which the products of combustion may pass upwardly to the space in the fire box above the arch. The inner 95 ends of the ribs 6 of these bricks 5, are cut away to form recessed seats for the adjacent arch tubes, and their inner ends are each provided with a rounded rib 8^a which engages and rests within the mortises 7 in the outer ends of the bricks 4 of the intermediate rows, thus locking the outer rows 100 of bricks to the intermediate rows and preventing them from having any tendency to ride up on their supporting arch tubes.

The bricks of each row 3, 4 and 5, are 110 locked together by mortise 9 and tenon 8 joint, but each of these rows is not connected

with others, so that there is but little chance for the bricks of one row becoming fused to those of the adjacent row, while those of each row are purposely connected so as to cause them to fuse, and become united. With an arch thus constructed defective or broken bricks will be retained in place, and may be readily broken apart to remove them when necessary to do so for the purpose of 10 making repairs.

The ribs 11 at the ends of the bricks of the side rows may be readily and quickly trimmed or chipped off in order to properly seat the brick 5 on the tubes 1, and give them 15 the proper inclination with relation to the side sheets and with each other, so that when assembled, the tenon 8 of one will enter the mortise 9 of the next adjacent brick in the same row.

20 The ribs on the underside of the bricks extend throughout the length of the latter, so that the gases and products of combustion in their passage under the arch will be retarded in their movements, and thoroughly commingled before passing into the space above the arch, and some will be deflected laterally against and over the tubes 25 and assist in heating the latter.

By providing the intermediate brick with 30 a mortise 7 at each end the bricks of the two rows will be interchangeable and engage the end tenons 8° of the bricks of the side rows.

Having fully described my invention what I claim as new and desire to secure by 35 Letters-Patent, is:—

1. An arch brick for locomotive fire boxes having a plurality of ribs on its lower face forming a plurality of channels, the said ribs and channels extending throughout the 40 length of the brick and the ribs being cut away to form curved seats to engage the arch tubes, the said seats being of less depth than the ribs so as to leave a passage way over the tubes, each brick also having a 45 mortise in one of its longitudinal edges and a tenon on its other longitudinal edge, whereby the bricks of each longitudinal row may be locked together.

2. The combination of a group of arch tubes, and an arch supported on said tubes, 50 the said arch composed of a series of rows of bricks extending lengthwise the fire box, the bricks of each row having a mortise and tenon connection, and the bricks of the adjacent rows having alining depending ribs 55 on their lower faces, the said ribs being cut away to form recessed seats to engage the arch tubes, the said seats being of less depth than the ribs so as to leave passage ways for the products of combustion over the tubes. 60

3. The combination of a group of arch tubes and an arch supported on said tubes, the bricks of the two outer rows of the arch each having a plurality of ribs on its lower face and outer end and the intermediate 65 bricks having ribs on their lower faces only, the ribs on the lower faces of the outer and intermediate rows being cut away to form curved seats to engage the arch tubes, the said seats being of less depth than the ribs 70 so as to leave passage ways for the products of combustion over the tubes.

4. An arch brick for locomotive fire boxes having a plurality of ribs on its underside which ribs are continued up one end of the 75 brick forming a plurality of gas deflecting channels under the entire brick and up one end of the latter.

5. The combination of furnace walls and a series of tubes arranged therein, of bricks 80 supported by said tubes and constituting the body portion of the baffle or arch, side rows of bricks supported by the outermost tubes, said side rows of bricks leaning against the walls of the furnace, all of said bricks having recesses or grooves designed to register with each other and forming continuous spaces around each of the tubes. 85

In testimony whereof I have signed this specification in the presence of two subscribing witnesses. 90
